DESIGN FOR A STRAINER

William C. P. Zabel and Richard C. Helfenbein,
Chicago, Ill.

Application June 13, 1945, Serial No. 120,042

Term of patent 14 years

(Cl. D44—29)

To all whom it concern:

Be it known that we, William C. P. Zabel and Richard C. Helfenbein, both citizens of the United States and both residents of Chicago, in the county of Cook and State of Illinois, have invented a new, original, and ornamental Design for a Strainer, of which the following is a specification, reference being had to the accompanying drawing, forming a part thereof, and in which:

Fig. 1 is a perspective view of a strainer showing our new design;

Fig. 2 is a top elevational view of the same;
Fig. 3 is a side elevational view of the same.

We claim:

The ornamental design for a strainer, as shown.

WILLIAM C. P. ZABEL.
RICHARD C. HELFENBEIN.
